UNITED STATES PATENT OFFICE.

CHARLES G. SMITH, OF MEDFORD, MASSACHUSETTS, ASSIGNOR TO RAYTHEON MANUFACTURING COMPANY, OF CAMBRIDGE, MASSACHUSETTS, A CORPORATION OF MASSACHUSETTS.

APPARATUS FOR HANDLING GASES AND VAPORS.

Application filed August 10, 1922. Serial No. 580,923.

To all whom it may concern:

Be it known that I, CHARLES G. SMITH, a citizen of the United States, residing at Medford, in the county of Middlesex and

5 State of Massachusetts, have invented certain new and useful Improvements in Apparatus for Handling Gases and Vapors; and I do hereby declare the following to be a full, clear, and exact description of the invention, such as will enable others skilled in the art to which it appertains to make and use the same.

10 The present invention relates to apparatus for handling gases and vapors and 15 more particularly to apparatus of this type employed for refrigerating purposes.

The application of Smith Serial No. 562,232, filed May 19, 1922, discloses a refrigerating apparatus in which the flow or circulation 20 of the refrigerating medium is accomplished in a new and novel manner. According to this application, the refrigerating medium is maintained at a relatively low absolute pressure in the evaporation 25 chamber and is pumped to the condensing chamber through a molecular gas pump, which derives its energy from a suitable source of heat. This gas pump may consist of one or more stages having properly 30 spaced and insulated hot and cold surfaces designed to divide the pump into different regions. From the pump the liquid vapor or gas passes into a chamber in which it is 35 condensed to a liquid and the resultant heat is dissipated in any suitable manner. From the condensing chamber the condensed liquid is returned to the evaporation chamber and the cycle of operations is repeated. It 40 will be evident to those skilled in the art that such an apparatus must be capable of not only dissipating the heat withdrawn by the evaporation of the liquid from the space to be refrigerated but in addition of dissipating the heat energy which is supplied to the 45 gas pump and not converted into useful work.

It is accordingly an object of the present invention to improve apparatus of this character in such a manner that the efficiency of 50 the apparatus is increased and the dissipation of heat facilitated.

A further object of the invention is to improve and increase the general efficiency of a gas pump of this general type and more

particularly such a pump comprising a plurality of stages.

With these objects in view the several features of the invention consist in certain novel features of construction, combinations and arrangements of parts hereinafter described and claimed, the advantages of which will be obvious to those skilled in the art from the following description.

In the accompanying drawing, Fig. 1 illustrates a view in elevation of a refrigerating apparatus embodying the features of the present invention, and Fig. 2 is a detail view, with parts broken away, of the disks hereinafter described.

The gas or vapor pump shown in the illustrated embodiment of the invention comprises essentially a series of hot surfaces indicated at 10 with a series of cold or relatively cooler surfaces indicated at 12. As described in the application hereinbefore referred to, the provision of these hot and cold surfaces properly spaced with relation to one another and having passages 10' and 12' of restricted size for the passage of gas molecules therethrough serves to cause a general movement of the gas or liquid vapor upwardly and at a progressively increasing pressure. The relatively small space separating the cold and hot surfaces is insulated in a manner to prevent any substantial transfer of heat therebetween, as fully explained in the application hereinbefore referred to. The hot surfaces may consist of a series of relatively thin metallic disks with suitable openings, the disks projecting radially from the outer periphery of a tube 15 of conducting material. If heat is imparted to the walls of the tube 15 it may flow outwardly through the material of the connected disks, retaining the surfaces at the desired temperature. This heat energy is supplied, as indicated, by an electric heating coil 18 received within the tube or by any other convenient source of heat energy, such as a gas flame. The opposing cold surfaces may be constituted by a series of similar disks extending inwardly from the outer walls of the pump and insulated from the adjacent hotter disks, as described. The cold surfaces are insulated from the heating tube 15 by a sleeve of insulating material surrounding the tube and the outer edges of the hot surfaces 10 are spaced away

from the outer shell to prevent any direct transfer of heat by metallic conduction therebetween. The evaporation chamber of the apparatus is indicated at 22 and the condensing chamber at 24, the two chambers being connected through the several stages of the gas pump. These chambers are hermetically sealed from the outer atmosphere by the casing 26 and have no connection with the interior of the heating tube 15. The refrigerating chamber 22 contains a refrigerating liquid, indicated at 30, of relatively low vapor tension, which is pumped from the refrigerating or evaporation chamber 15 into the condensing chamber through the medium of the molecular pump. As fully described in the application referred to, this pumping action in general is caused by the energetic rebound of gas molecules from the heated surface in the general direction of flow of the gas, these molecules abstracting energy from the heated surface upon impact therewith. By suitably coordinating the openings or passages through the hot and cold surfaces with the mean free path of the molecules at any given pressure of the gas, any substantial movement of the molecules in a direction opposite to the direction of rebound is precluded. A general movement of molecules in the desired direction is initiated in certain of the regions of convection, the molecules passing from one region into the next, where additional energy is imparted. It will be evident that this operation may be carried out with one or more stages of the pump.

It is desirable in apparatus of this character to facilitate the dissipation of heat from the apparatus and to this end the present invention contemplates more particularly a new and improved method of accomplishing this result through the employment of the condensed refrigerant. To this end the outer periphery of the molecular pump is enclosed by a funnel shaped wall 32 which gradually tapers inwardly from the first to the last stage of the pump in such a manner that the effective area of the first stage is materially greater than the effective area of the last stage of the pump. This wall consists of material which conducts heat freely and in conjunction with the outer casing provides a liquid containing receptacle or trough 34 in which the condensed refrigerating liquid is collected. The cold disks or plates 12 are connected directly to the wall 32 and serve to conduct heat to the wall. This heat is transferred to the condensed liquid 34 and the latter being at a relatively low absolute pressure boils or evaporates when an excess of heat is supplied. This secondary evaporation of the liquid serves to abstract relatively large quantities of heat from the liquid and the surrounding walls 65 and the vapor produced thereby rises in a

condensing chamber 24 and is condensed on the walls in the usual manner, this heat being dissipated through the usual conducting fins 36 projecting outwardly from the casting, or by some equivalent form of construction. The condensed vapor or gas is returned from the wall of the condensing chamber to the space 34, an annular trough 40 serving to collect liquid which may have condensed on the wall of tube 15. A return pipe 42 passing downwardly from the space 34 to the evaporation chamber serves to return the liquid to the evaporation chamber, the pipe 42 being provided with a trap 44 at the lower end, as indicated. This form of construction greatly increases the ability of the apparatus to dissipate heat, more especially heat from the molecular pump. It will be evident that with this construction the waste heat from the pump is easily conveyed to the condensing chamber, where an ample radiating surface may be provided for its dissipation, making it unnecessary to dissipate this heat entirely from the walls surrounding the pump or by conduction through the material of the walls from the region surrounding the pump to the condensing region. The provision of this means for dissipating the heat furthermore permits the outer casing to be formed of a material which may be a relatively poor conductor of heat and thus insures that the amount of heat passing through the walls by conduction from the condensing region to the evaporation region will be negligible. As the pressure of the gas in successive stages of the pump increases, the effective area of hot surface required for the insulation of the gas is less and the provision of the tapering funnel shaped wall of the molecular pump provides a simple and convenient method of reducing this cross section. As indicated in the drawings, the molecular pump gradually decreases in effective area throughout successive stages.

I claim:

1. In apparatus of the character described, means including a pair of members at different temperatures and in spaced relation to each other for pumping a gaseous medium in response to said temperature difference, means whereby said member of higher temperature is heated, and means for supporting a cooling liquid in heat transfer relation to said member of lower temperature.

2. In apparatus of the character described, means for pumping a gaseous medium in response to a temperature difference between separate portions thereof, a source of heat for said portion of higher temperature, and means for supporting a vaporizable cooling liquid in heat transfer relation to said portion of lower temperature.

3. In apparatus of the character de-

scribed, means for pumping a gaseous medium in response to a temperature difference between separate portions thereof, a source of heat for said portion of higher temperature, 5 means for supporting a vaporizable cooling liquid in heat transfer relation to said portion of lower temperature, and means for condensing the vaporizable liquid and returning the condensed liquid to its 10 position in heat transfer relation to said portion of lower temperature.

4. In apparatus of the character described, means for pumping a gaseous medium in response to a temperature difference 15 between separate portions thereof, a source of heat for said portion of higher temperature, an evaporation chamber at the lower pressure side of said pumping means, and means for condensing vapor propelled 20 through said pump from said evaporation chamber and depositing the condensed liquid in heat transfer relation to said portion of lower temperature to cool said portion.

5. In apparatus of the character described, 25 stationary means for pumping a gaseous medium in response to a temperature difference between portions thereof and means whereby said difference in temperature is maintained, including a source of 30 heat for said portions of higher temperature, and means for supporting a cooling liquid in heat transfer relation to said portion of lower temperature.

6. In apparatus of the character described, 35 an evaporation chamber, a condensing chamber and means including a pair of members at different temperatures and in spaced relation to each other for pumping a gaseous medium for said evaporation chamber to 40 said condensing chamber in response to the said temperature differences, means whereby said member of higher temperature is heated, and means for receiving and collecting liquid from the condensing chamber in heat 45 transfer relation to said member at lower temperature for cooling said member.

7. In apparatus of the character described, 50 means including a pair of members at different temperatures and in spaced relation to each other for pumping a gaseous medium in response to said temperature difference, a container for sealing said pumping means from the atmosphere, means external of said 55 container for transmitting heat to said member of higher temperature, and means within said container for supporting a cooling liquid in heat transfer relation to said member of lower temperature.

8. In apparatus of the character described, 60 means including a pair of members at different temperatures and in spaced relation to each other for pumping a gaseous medium in response to said temperature differences, a container for sealing said pumping means 65 from the atmosphere, said container hav-

ing a wall in heat transfer relation to one of said members, and means within said container for supporting the cooling liquid in heat transfer relation with one of said members.

9. In apparatus of the character described, 70 means including a pair of members at different temperatures and in spaced relation to each other for pumping a gaseous medium in response to said temperature difference, a container for sealing said pumping means from the atmosphere, said container having a wall in heat transfer relation to one of said members and having a recess, the wall of which is in heat transfer relation to 75 the other of said members, a heating element in heat transfer relation to one of said walls, and means for supporting a cooling liquid in heat transfer relation to the other of said walls.

10. In apparatus of the character described, 80 means including a pair of members at different temperatures and in spaced relation to each other for pumping a gaseous medium in response to said temperature difference, 85 a container for sealing said pumping means from the atmosphere, said container having a wall in heat transfer relation to one of said members and having a recess, the wall of which is in heat transfer relation to the other of said members, a heating element in said recess to transmit 90 heat to the wall thereof, and a cooling liquid in heat transfer relation to the other of said members.

11. In apparatus of the character described, 95 a fluid passageway, hot and cold surfaces disposed transversely of said passageway at spaced intervals and facing in opposite directions, a passage available for the movement of gas molecules past said surfaces, the width of said passage being comparable to the mean free path of the gas molecules, and means for supporting a 100 cooling liquid in heat transfer relation to said cold surfaces.

12. Apparatus of the character described 105 having a fluid passageway, perforated plates disposed transversely of said passageway at spaced intervals, oppositely directed surfaces of recurrent plates having greater 110 ability to interchange heat with the fluid than the other surface of the same plates, and means associated with the latter surface for bringing a liquid into heat-conductive relationship thereto.

13. Apparatus of the character described 115 having a fluid passageway, perforated plates disposed transversely of said passageway at spaced intervals, oppositely directed surfaces of recurrent plates having greater 120 ability to interchange heat with the fluid than the other surfaces of the same plates, and means whereby certain of the plates may be heated, and means whereby certain 125

other of the plates may be cooled by a circulating liquid.

14. Apparatus of the character described having a fluid passageway, perforated plates disposed transversely of said passageway at spaced intervals, one set of recurrent plates having greater ability to interchange heat with the fluid on one side, and another set of recurrent plates having greater ability 10 to interchange heat with the fluid on the opposite side, and means whereby one set of plates may be heated and means where-

by the other set of plates may be cooled by a circulating fluid in heat conducting relationship thereto.

15. Apparatus of the character described having a fluid passageway, perforated plates disposed transversely of said passageway at spaced intervals, one surface of each plate having greater ability to interchange heat 20 with the fluid than the other surface, and a liquid in heat conducting relationship to the latter of said surfaces.

CHARLES G. SMITH.
